GUIDE FOR ATTACHMENT TO NEWSPAPER-
CONTAINING RECEPTACLES

Ralph E. White, Alpine, Oreg.

Application September 3, 1948, Serial No. 47,607

2 Claims. (Cl. 232—1)

1

This invention relates to a guide for attachment to a newspaper-containing receptacle, and more particularly to a guide of the type for insuring the entry of a newspaper into the receptacle when placed thereon.

An object of the invention is to provide a guide for attachment to the open end of a newspaper-containing receptacle which will positively insure the entry into the receptacle of the newspaper when forcibly projected thereon.

Another object of the invention is to provide a guide for attachment to the open end of a newspaper-containing receptacle which will positively insure the entry into the receptacle of the newspaper when forcibly projected thereon from a moving vehicle, and which will prevent the newspaper from bouncing out of the receptacle.

A further object of the present invention is to provide a guide for attachment to the open end of a newspaper-containing receptacle which is simple in structure and which may be readily attached to or detached from the open end of said receptacle.

Other objects and advantages will become apparent from the following description.

An embodiment of the invention is illustrated by way of example in the accompanying drawings, wherein:

Figure 1 is a side elevational view showing the guide according to the present invention attached to the open end of a newspaper-containing receptacle;

Figure 2 is a sectional view taken on the line 2—2 of Figure 3;

Figure 3 is an end elevational view of the guide shown in Figure 1;

Figure 4 is a sectional view taken on the line 4—4 of Figure 2.

Referring to the drawings, the numeral 10 designates a tubular-shaped newspaper-containing receptacle or holder having one end 17 closed and its opposite end 9 open, the open end of said receptacle being provided with a rolled edge or annular bead 12. Arranged in abutting relation with respect to the open end of the receptacle 10 is a guide 13 attached thereto, the guide being a body of sheet metal or similar thin walled material having a substantially semi-circular cross sectional shape. The front end of the guide 13 is provided with a tapering projection or nose 14. The rear end of the guide 13 is turned inwardly so as to form a collar 18, the collar being of a size greater than a semi-circle but less than a full circle, with its ends spaced from each other. The collar 18 embracingly

2

engages the rolled edge or bead 12 of the holder 10, and the guide is provided adjacent the collar 18 with an internal groove formation 22 receiving the rolled edge 12 of the holder. The ends of the collar 18 are extended as indicated at 19 and 20 to bear against the exterior side of the holder 10 adjacent the rolled edge or bead 12 to retain the guide 13 in position on the bead 12. Adjacent the groove formation 22 the guide has 10 an inwardly inclined lip formation 15 which bears against the rolled edge or bead 12 of the holder so that this bead is resiliently clamped between the collar 18 and the lip formation 15.

With the guide 13 in assembled position on the holder 10, a newspaper forcibly projected thereon from a moving vehicle will be directed inwardly and over the lip 15 into the interior of the holder. Should the projecting force of the newspaper be such that it strikes the closed end of the holder 20 and rebounds forwardly, the lip 15 serves to arrest the forward movement of the newspaper, thereby causing it to be retained in the holder.

The interior face of the guide 13 has lettering 21 thereon for indicating the days when papers 25 are to be delivered to each domicile. This lettering is arranged in upright position for the particular direction of approach to the receptacle, as shown in full lines in Figures 1 and 2. For the opposite direction of approach, the guide 30 would be shifted over to the opposite side of the receptacle, in which case the lettering would have to be applied in the inverted position, as indicated in broken lines, relative to the full line indication thereof.

From the foregoing description and a study of the drawings, it will be apparent that I have provided a new construction. It is, of course, to be understood that I reserve the right to make such changes in the form, construction and arrangement of parts as will not depart from the spirit of the invention or the scope of the appended claims.

I claim:

1. In combination with a tubular newspaper holder having an open end and a rolled edge surrounding such open end, a guide for directing newspapers into such holder comprising a thin walled body of substantially semi-circular cross sectional shape laterally extended at one end and rolled to provide a collar extending through an arc greater than a semi-circle and embracingly engaging said holder behind the rolled edge of the latter, said body also having an internal groove formation adjacent said 50 collar receiving the rolled edge on said holder,

and an inwardly inclined lip formation adjacent said groove formation and overlying said rolled edge to resiliently clamp said rolled edge between said collar and said lip formation and thereby secure said guide in outwardly extending relationship to said holder at one side of the open end of the latter.

2. In combination with a tubular newspaper holder having an open end and a rolled edge surrounding such open end, a guide for directing newspapers into such holder comprising a thin walled body of substantially semi-circular cross sectional shape laterally extending at one end and rolled to provide a collar extending through an arc greater than a semi-circle and embracingly engaging said holder behind the rolled edge of the latter, said body also having an internal groove formation adjacent said collar receiving the rolled edge on said holder, and an

inwardly inclined lip formation adjacent said groove formation and overlying said rolled edge to resiliently clamp said rolled edge between said collar and said lip formation and thereby secure said guide in outwardly extending relationship to said holder at one side of the open end of the latter, said body being tapered at its opposite end to provide an outwardly extending nose.

RALPH E. WHITE.
